Walter Piessell

Seller's Patent

9514X

The Schedule referred to in these Seller's Patent and making part of the same containing a description in the words of the said Walter Piessell himself of his improvement in the machine for breaking stones.

To all whom these presents shall come

Be it known that of John Piessell of the Town of Lexington in the County of Mercer and State of Kentucky have invented a new and useful break and that the following is a full and exact description thereof. Two well made feet long, framed together with eight timber three feet long, the hand and swords as of a common break the hinder end of the lower swords being incorporated into a eight piece of timber framed into the uprights four feet six inches high to the eight piece wherein the hinder end of the upper swords are incorporated are two stamp arms from which chains are suspended and the common stars fastened to the springs there being five springs which is designed to be worked under much horizontality of but may be worked suspendedly at the hinder end of the break. The machinery is worked and put in motion by means of two timbers eight feet long, connected together by a eight piece of timber four feet long. What I claim as my own invention and not previously known in the above described machine is the applying of springs to a break and the working of it by a timber and the great additional force that the machine exerts in its operation by means of the stamp arms which is entirely my own invention.
